UNITED STATES PATENT OFFICE.

JOHN B. CANTWELL, OF WATERTOWN, NEW YORK.

ROTARY CUTTER.

No. 892,977.

Specification of Letters Patent.

Patented July 14, 1908.

Application filed May 7, 1907. Serial No. 372,369.

To all whom it may concern:

Be it known that I, JOHN B. CANTWELL, a citizen of the United States of America, residing at Watertown, in the county of Jefferson and State of New York, have invented certain new and useful Improvements in Rotary Cutters, of which the following is a specification, reference being had therein to the accompanying drawings.

10 The invention relates to dredging or excavating apparatus of that type in which the material is carried away through a suction pipe.

More particularly the invention relates 15 to the construction of a rotary cutter connected at the end of the suction pipe.

In the present state of the art, suction pipes have been provided with rotary cutters at the end thereof which sever the soil 20 into strips or sections which may then be carried by the water current passing through the suction conduit. With such constructions of cutter, considerable difficulty is experienced in preventing clogging by the lodging 25 of masses of clay or soil between the cutter blades or about the rotating member upon which they are mounted. Thus if this member is in the form of a shaft passing centrally through the suction conduit, it 30 obstructs a valuable portion of the passage. On the other hand, if the conduit is rotated and the blades attached thereto, the outer ends of said blades are subjected to torsional stress.

35 It is a special object of the present invention to obtain a construction which is free from obstruction to the passage of the soil and yet one which is strongly braced against torsional stresses.

40 To this end, the invention consists in the construction as hereinafter set forth.

In the drawings, Figure 1 is a longitudinal section through the cutter; and Fig. 2 is a sectional end elevation thereof.

45 A is a rotary suction conduit, at the outer end of which is attached a rotary cutter B. This cutter comprises a flaring sleeve C which is secured to the end of the conduit A and a series of longitudinally-extending 50 blades D attached at their inner ends to the flaring sleeve and at their outer ends bent towards the center and connected to a common head E. Each of the blades D is inclined to the path of rotation so as to sever a strip from the matter in contact with which 55 the cutter is rotated and direct the same

into the suction conduit. The blades are further provided with cross-cutters D' attached to the longitudinal cutters and parallel to the plane of rotation by which the 60 severed strip is sub-divided into narrow sections. With the construction as thus far described, the driving of the blades is effected solely through their attachment with the flaring sleeve C and consequently 65 the outer ends will be subjected to considerable torsional stress, endangering the life of the cutter. I have therefore provided a brace for connecting the head E with the sleeve C but so arranged as not to form an 70 obstruction in the path of the material entering the suction conduit. This brace is formed by a plurality of inclined arms F connected at one end to the sleeve C near the periphery thereof and at the opposite 75 end to the head E near the center. Each blade is of a cross section that is of greater depth than width and thus the surface exposed in the path of the soil is very small. Furthermore, the attachment to the sleeve C being near the periphery, abundant clearance is provided for the passage of the material, whereas a construction provided with a central drive shaft places an obstruction in the most contracted portion of the conduit. 85

I preferably form a brace with three arms F integrally connected at their outer ends with a tapering pin G passing through an oppositely tapered recess in the head E and 90 the parts are then firmly clamped to each other by a tapering sleeve H and a clamping nut I bearing thereon and engaging a threaded stud J extending outward from the pin G. The inner ends of the arms F may 95 be riveted or otherwise secured to the sleeve C.

In operation, the rotation of the conduit A and attached sleeve C will be directly communicated to the head E through the medium 100 of the brace arms F and in this way torsional stress upon the blades D is avoided. The material severed into narrow strips by the combined action of the blades D and cross-cutters D' will easily pass into the suction 105 conduit through the flaring mouth formed by the sleeve C.

What I claim as my invention is,—

1. The combination with a suction conduit, of a cage at the end thereof comprising 110 a series of longitudinally-extending blades and means connecting the inner ends of the

blades by which said blades are rotated arranged outside of the path of the material entering the conduit.

2. The combination with a suction conduit, of a cutter at the end thereof, comprising a series of longitudinally-extending blades, means outside the path of the material entering the conduit connecting the inner ends of said blades and a brace extending therefrom to the outer ends of said blades to relieve the latter from torsional stress.

3. The combination with a suction conduit, of a sleeve at the end thereof, a series of longitudinally-extending blades connected to said sleeve and a brace extending from said sleeve to the outer ends of said blades to relieve the same from torsional stress.

4. The combination with a suction conduit, of a flaring sleeve at the end thereof, a series of longitudinally-extending blades connected to said sleeve and a brace extending from the flaring portion of said sleeve to the outer ends of said blades to relieve the latter from torsional stress.

5. The combination with a sleeve or mouth-piece for a suction conduit, of a series of longitudinally extending cutter blades bent longitudinally inward at their outer ends, a head to which the outer ends of said blades are attached and a brace extending from said head to said sleeve or mouth-piece.

6. The combination with a sleeve or mouth-piece for a suction conduit, of a series of longitudinally extending blades bent radially inward at their outer ends, a head to

which the outer ends of said blades are attached and a brace comprising a plurality of inclined arms extending from the central portion of said head to said rotary sleeve.

7. A rotary cutter comprising a flaring sleeve constituting the mouth-piece of a suction conduit, a series of longitudinally-extending cutter blades attached to said sleeve and bent radially inward at their outer ends, a head to which said blades are attached and a brace comprising a plurality of inclined arms centrally connecting to said head at their outer ends and attached to the flaring portion of said sleeve at their inner ends.

8. A rotary cutter comprising a flaring sleeve or mouth-piece for a suction conduit, a series of longitudinally-extending blades attached thereto and bent radially inward at their outer ends, a head to which the outer ends of said blades are attached having a tapering central aperture therein, a brace member having an oppositely-tapering pin extending into said aperture and a plurality of inclined arms extending to the flaring portion of the sleeve, a tapering sleeve fitting between said pin and head, a threaded stud on said pin and a clamping nut engaging said stud for tightening said flaring sleeve to clamp said brace to said head.

In testimony whereof I affix my signature in presence of two witnesses.

JOHN B. CANTWELL.
